CONTACTOR

Edward L. Brazil, Crows Landing, Calif.

Application June 30, 1947, Serial No. 758,120

11 Claims. (Cl. 200—152)

1

This invention is directed to, and it is an object to provide, a novel switch or contactor operative to recurringly make and break the circuit for a pump motor in a liquid pumping system; the contactor being responsive to the level of a liquid in a reservoir to which the pump is connected.

In certain liquid pumping systems, as for example in milk processing plants, the liquid is fed from one source to a receiving reservoir and then intermittently pumped from the reservoir for subsequent handling; the pump being started each time the liquid in the reservoir reaches a predetermined high level, and stopped when the liquid is at a predetermined low level.

The present invention thus has for another of its objects the provision of a novel float valve controlled contactor for the circuit of a pump motor in a liquid pumping system as above; the float valve being arranged in a unique manner to cause the contactor to close the pump motor actuating circuit each time that the high level is reached in the reservoir, and to open such circuit when the liquid is pumped down to the low level.

Another object of this invention is to provide a float valve controlled contactor, as above, wherein opening of such contactor to break the circuit and stop the pump motor is accomplished, at the correct time, by what may be termed "delayed action" of the float valve, and which function will hereinafter appear in detail.

An additional object of the instant invention is to provide a contactor, for the purpose, which includes normally spaced contact elements, the circuit between which is adapted to be closed by liquid in the reservoir; access of such liquid to the elements being controlled by the novel arrangement of the float valve therewith.

A further object of the invention is to provide a simple, practical and convenient contactor which will be exceedingly effective for the purpose for which it is designed.

These objects are accomplished by means of such structure and relative arrangement of parts as will fully appear by a perusal of the following specification and claims.

In the drawings:

Fig. 1 is a sectional elevation of the contactor with the float controlled valve open.

Fig. 2 is a similar view, but shows the valve closed.

Fig. 3 is an elevation of the device as suspended in a reservoir for use; the reservoir being shown

in section, and the pump motor control circuit diagrammatically.

Referring now more particularly to the characters of reference on the drawings, the contactor is constructed in the manner shown in Figs. 1 and 2, and comprises an upstanding tubular body 1 fitted, at the upper end, with a dielectric head 2 removably held in place by a top retaining nut 3.

10 An electrode 4 is mounted in connection with the dielectric head 2 and depends therefrom into the tubular body 1 in clearance relation to the sides thereof; the electrode terminating adjacent, but short of, the lower end of said body. 15 Above the dielectric head 2 the electrode 4 is formed with an electrical connection fitting 5.

The lower end of the tubular body 1 is normally closed by a removable bottom 6 held in place by a bottom retaining nut 7.

The bottom 6 is formed, centrally thereof, with a downwardly opening tapered valve seat 8, and a bore 9 leads from such seat axially upwardly through the bottom 6. A tapered plug valve 10 cooperates with the tapered seat 8, and includes 25 an upwardly projecting stem 11 which slidably engages in the bore 9 and terminates thereabove. A cross pin 12, through the stem 11 above the bottom 6, permits the tapered plug valve 10 to move vertically between open and closed positions 30 without escape from the device.

The bottom 6 is formed with a bleed passage 13 which leads downwardly from the top surface of said bottom 6 to entry into the tapered seat 10 intermediate its ends. With this arrangement liquid can flow from within the tubular body 1, through the bleed passage 13, and escape only when the tapered plug valve 10 is open, as in Fig. 1; the flow being controlled by the diameter of such bleed passage. When the tapered plug valve is closed, as in Fig. 2, the bleed passage 13 is also effectively closed.

At its lower end the tapered plug valve 10 is formed with an air bell or float 14 which depends therefrom in actuating relation to said valve.

45 Adjacent but short of its upper end the tubular body 1 is formed with a circumferential row of spaced ports 15 of relatively small diameter. Above this row of ports 15 the tubular body 1 includes a single vent port 16.

The above-described contactor is employed in the manner shown in Fig. 3, wherein said contactor is suspended by any suitable means, as for example a bracket 17 in a reservoir 18 from which a liquid 19 is to be pumped. The liquid 19 is fed into the reservoir 18 by

means not shown, and is pumped out of said reservoir through a pipe 20 connected to the reservoir adjacent the bottom thereof. A pump 21 is interposed in the pipe 20 and is adapted to be driven by an electric motor 22 energized through the medium of a main circuit 23. This main circuit 23 has a control switch 24 interposed therein, and such switch is of relay type, including a coil 25 adapted to control opening and closing of the switch 24. The coil 25 works at extremely low voltage, and is interposed in a control circuit 26. The control circuit is energized by a transformer 27 interposed therein, which transformer is fed from the main circuit 23 ahead of the switch 24. The control circuit includes a lead 28 attached to the electrical connection fitting 5 of the electrode 4. The reservoir 18 is grounded, as is one side of the transformer 27, to complete the control circuit 26. This control circuit 26 is initially open.

When the contactor is suspended in the reservoir 18, the float 14 depends slightly below predetermined low level 29 for the liquid 19, while the row of ports 15 is disposed closely adjacent a predetermined high level 30.

Assuming that the liquid 19 in the reservoir is at the low level 29, but additional liquid is flowing into such reservoir, the contactor works as follows to control operation of the pump 21, which is initially not in operation:

As the liquid 19 rises above the low level 29, the float correspondingly rises, closing the tapered plug valve 10 ahead of the liquid level. Thus, as the liquid level rises beyond the lower end of the tubular body 1, the valve 10 is closed and no liquid can enter said body.

The liquid level continues to rise in the reservoir 18 until the high level 30 is reached, and when this occurs liquid flows through the row of ports 15, filling the tubular body 1 up to such row; the vent port 15 preventing any back pressure in said body.

With liquid filling the body 1, the control circuit 26 is closed between the electrode 4 and tubular body 1; i. e. between such electrode 4 and the grounded reservoir 18. This causes energization of the coil 25 and closing of the relay switch 24. With switch 24 closed, the main circuit 23 energizes the motor 22, with resultant operation of the pump 21.

The pump 21 then functions to withdraw the liquid 19 from the reservoir until such liquid lowers from the high level 30 to adjacent the low level 29; the float 14 holding the valve 10 closed during this period. When the liquid 19 approaches the low level 29 the float 14 drops open by gravity, opening the valve 10 and permitting the liquid within the tubular body 1 to drain out through the bleed passage 13 and the open valve seat 8. When this occurs the control circuit 26 between the electrode 4 and tubular body 1 breaks, deenergizing the coil 25 and permitting opening of the switch 24. As the switch 24 opens, motor 22 and pump 21 cease operation and no further pumping takes place until the reservoir 18 is again filled to the high level 30. The contactor thus provides a very well-timed cycling of operation of the motor driven pump 21 at not too frequently recurring times; i. e. the motor can be brought into operation at a predetermined high level of the liquid and taken out of operation at a predetermined low level in an effective manner. Further, the described float valve arrangement, in combination with the tubular body 1, provides the "delayed-action" means necessary

to keep the motor in operation during the pumping portion of the cycle. The row of ports 15 are of relatively small diameter in order to prevent the entry of surface foam into the tubular body 1, which might otherwise impair proper operation of the contactor.

The contactor while working in the liquid 19 is safe for the reason that the control circuit 26 works on a very low voltage, as described, and there is no risk to any attendant who may come in contact with the reservoir 18 or other part of the control circuit.

The electrode 4 is elongated and terminates adjacent, but short of, the bottom 6, for the following reason:

As the liquid approaches the low level and the valve 10 opens, with resultant draining of the liquid from the tubular body 1 through bleed passage 13, the control circuit remains closed and does not break until the liquid in said tubular body breaks away from the lower end of the electrode 4. In this manner the motor driven pump is actuated somewhat longer than would be the case if the electrode 4 terminated closely adjacent the row of ports 15.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A control circuit contactor adapted to be mounted in a liquid reservoir in responsive relation to predetermined high and low levels therein, said contactor including spaced elements initially open in the control circuit, but arranged to be closed in said control circuit by liquid contact therebetween upon the liquid reaching the high level, and delayed-action means operative to then maintain said liquid contact between the elements until the liquid in the reservoir approaches said low level, said delayed action means including a float valve.

2. A control circuit contactor adapted to be mounted in a liquid reservoir in responsive relation to predetermined high and low levels therein, said contactor including an upstanding, hollow body in the reservoir in position to fill with liquid when the same reaches said high level, a float valve in communication with the body adjacent its lower end adapted to release liquid from the body when the liquid in the reservoir approaches said low level, and an electrode in the body in dielectric relation thereto.

3. A contactor adapted to be closed by entry of liquid thereinto and opened upon discharge of the liquid, comprising an upstanding, hollow body, a float valve communicating with the body at one point, the body having means for liquid entry above said point, and an electrode in the body, in dielectric relation thereto, below said entry means but terminating above said point.

4. A contactor adapted to be closed by entry of liquid thereinto and opened upon discharge of the liquid, comprising an upstanding, hollow body, a float valve communicating with the body at one point, the body having means for liquid entry above said point, and an electrode in the body, in

dielectric relation thereto, below said entry means but terminating above said point; said entry means being a circumferential row of ports in the body.

5. A contactor adapted to be closed by entry of liquid thereinto and opened upon discharge of the liquid, comprising an upstanding, hollow body, a float valve communicating with the body at one point, the body having means for liquid entry above said point, and an electrode in the body, in dielectric relation thereto, below said entry means but terminating above said point; said entry means being a circumferential row of ports in the body, said ports having a relatively small diameter.

6. A contactor adapted to be closed by entry of liquid thereinto and opened upon discharge of the liquid, comprising an upstanding, hollow body, a bottom in the body, said bottom having a valve seat in communication with the interior of the body, a valve cooperating with the seat and movable upward to closed position, a float below the valve and connected thereto, the body having liquid entry means therein some distance above the bottom, and an electrode in the body, in dielectric relation, terminating at its lower end between the entry means and said bottom.

7. A contactor adapted to be closed by entry of liquid thereinto and opened upon discharge of the liquid, comprising an upstanding, hollow body, a bottom in the body, said bottom having a valve seat in communication with the interior of the body, a valve cooperating with the seat and movable upward to closed position, a float below the valve and connected thereto, the body having liquid entry means therein some distance above the bottom, and an electrode in the body, in dielectric relation, terminating at its lower end between the entry means and said bottom; the valve seat and valve being tapered, and a bleed passage in the bottom thereof extending between its top surface and a point on the valve seat intermediate its ends.

8. A contactor adapted to be closed by entry of liquid thereinto and opened upon discharge of the liquid, comprising an upstanding, hollow body, a

dielectric head on the body, an electrode depending from the dielectric head into the body in spaced relation, a float valve in communication with the body below the lower end of the electrode, and the body having liquid entry means therein intermediate the ends of the electrode.

9. A contactor adapted to be closed by entry of liquid thereinto and opened upon discharge of the liquid, comprising an upstanding, hollow body, a dielectric head on the body, an electrode depending from the dielectric head into the body in spaced relation, a float valve in communication with the body below the lower end of the electrode, and the body having liquid entry means therein intermediate the ends of the electrode; said liquid entry means being a circumferential row of ports in the body.

10. A contactor adapted to be closed by entry of liquid thereinto and opened upon discharge of the liquid, comprising an upstanding, hollow body, a dielectric head on the body, an electrode depending from the dielectric head into the body, an electrode depending from the dielectric head into the body in spaced relation, a float valve in communication with the body below the lower end of the electrode, and the body having liquid entry means therein intermediate the ends of the electrode; said liquid entry means being a circumferential row of ports in the body, the latter having a vent port above said row.

11. A contactor, as in claim 8, in which the body includes a bottom with which the float valve is connected, both the dielectric head with the electrode, and the bottom with the float valve, being removable from the body.
